his ATTORNEY

UNITED STATES PATENT OFFICE

CHARLES BERGER, OF MAPLEWOOD, NEW JERSEY, ASSIGNOR TO GROOVE LOCK CO. INC.,
OF NEW YORK, N. Y., A CORPORATION OF NEW YORK

VANITY CASE

Application filed August 1, 1929. Serial No. 382,689.

This invention relates to receptacles, the invention being more particularly related to vanity cases; and the invention has for its purpose and object the provision of an improved construction of this character which will embody certain desired features of simplicity, efficiency and convenience, and which will be economical to manufacture.

More particularly, the object of the present invention is to provide certain improvements in that type of vanity cases which embody hinge connected sections consisting of a body section and a lid closure section for the body, the improvements relating to a simplified finger piece which is mounted to the body section for sliding movement relatively thereto, and to a simplified retaining device arranged on the lid closure section and adapted, when the hinge connected sections are closed, to be engaged by the finger piece to hold said section firmly in closed relation.

An object of the invention is the provision of a finger piece and cooperating retaining device of the character described, which are especially adapted for use in connection with a body section and a lid closure section connected by a spring hinge and in a manner as hereinafter described so that only a slight movement of the finger piece will be necessary in order to permit the lid closure section to open automatically.

A further object is to so construct the finger piece and cooperating retaining device that they may be associated respectively with a body section and lid closure section of substantially uniform size and shape; and still further to so mount the finger piece that the slot or slideway in which it has relative movement will be concealed from view. A still further object is to so construct and mount the finger piece that it will be held in the position to which it is moved without the use of a spring.

Other objects and aspects of the invention will appear hereinafter.

The invention consists in the improved vanity case, and in the form, construction and relative arrangement or arrangements of parts as will be hereinafter more fully de-

scribed and subsequently pointed out in the claims.

The invention will be best understood by referring to the accompanying drawings, which form a material part of this application, and in which:—

Figure 1 represents a front elevational view of my improved vanity case, showing the sections in open relation;

Fig. 2 represents a top plan view of the vanity case;

Fig. 3 represents a fragmentary sectional view, taken on the line 3—3 of Fig. 1;

Fig. 4 represents a cross sectional view on a relatively large scale, showing the retaining device interlocked with the finger piece; and

Fig. 5 represents an enlarged perspective view of the finger piece detached.

The preferred form of construction, as illustrated in the accompanying drawings, comprises a receptacle consisting of a circular body section 10 formed with an annular upstanding flange 11, and a circular lid closure section 12 formed with an annular flange 13 adapted, when the sections are in closed relation to meet the flange 11 edge to edge. The sections are united for opening and closing movement by a hinge structure 14 which connects the flange 11 of the body section with the flange 13 of the lid closure section; the hinge structure 14 preferably being a spring hinge structure of any suitable or approved type adapted to urge the sections into open relation and to maintain them in open relation, as shown in Figs. 1 and 2.

In carrying the invention into effect according to the preferred form of construction, the annular flange 11, preferably at a point diametrically opposite the transverse center line of the hinge structure, is provided with a vertical recess 15 which extends downwardly into the body of the flange along the inside face thereof and communicates with one end of a horizontal slot slideway 16 provided in the body of the flange and extending, in the present instance, below the communicating vertical recess 15 from a point 17 (Fig. 3) to a point 18 at the right of the open communication with said recess. The finger

piece is designated generically by the reference character 19 and is composed of a finger-hold 20 and an integral body part 21 which slidably fits within the slot slideway 16 for movement between the points 17 and 18 which serve as end terminals, the length of the body part 21 being such that when it abuts the terminal 18, that portion of the slot slideway which comes below the vertical recess 15 will be clear for the reception of a hook member 22 depending from the edge of the annular flange 13 of the lid closure section. The body part 21 of the finger piece is formed along its inner face with two shoulder extensions 23 and 24 spaced apart as best shown in Fig. 4. The shoulder extension 23, which is the upper extension, is adapted, when the lid closure section has been closed with the hook member 22 inserted through the recess 15 and into the slideway, to be engaged over the outwardly projecting end 25 of the hook member, such engagement obviously being effected by moving the finger piece from a position in abutment against the terminal 18 to a position in abutment against the terminal 17. When the lid closure section has been closed and the finger piece has thus been moved against the terminal 17 the sections will be maintained in closed relation with their flanges meeting edge to edge. Through the engagement of the shoulder extension 23 with the hook member 22 a positive interlocking action is obtained which holds the lid closure firmly in closed position upon the body section.

35 The shoulder extension 24, comprising the lower extension, is made with a lip portion 26 which is engaged over and may be joined to an elongated strip 27 having oppositely extending wing portions 28 which extend well beyond the finger piece. As clearly illustrated in Fig. 4, the elongated strip 27 with its wing portions 28 slidably fits along the inner concave face of the flange 11, being held in frictional contact therewith by the lip 26.

40 In this way, the finger piece is operatively held in position against displacement and at the same time the wing portions 28, which are of a resilient character, serve as means whereby frictionally to maintain the finger piece in the position to which it is moved.

According to a feature of my improvements, the finger-hold 20 is of such relative length with respect to the slot slideway 16 that said slot slideway will be completely concealed irrespective of the position of the finger piece, whether abutting the terminal 18 or abutting the terminal 17. This arrangement is also such that, at the inner face of the flange 11, the slot slideway as well as the vertical recess will be concealed from view by means of the bessar or ring 29 which fits the inner periphery of the flange 11.

In use, assuming that the lid closure section is closed and locked in closed position by the finger piece, it is only necessary in order to

permit automatic opening of the lid closure section, to move the finger piece from the position where the body part 21 abuts the terminal 17 to the position where said body part will abut the terminal 18. On the other hand, when it is desired to secure the lid closure section in closed position, it is only necessary to move the sections towards each other until the flanges thereof come into contact, when the finger piece is moved to the left so as to engage the shoulder extension 23 over the hook 25 of the hook member.

Although the receptacle shown by way of example in the accompanying drawings is in the form of a vanity case, it will be understood that the principle of the invention may be practiced in connection with receptacles other than vanity cases and of different shapes.

From the foregoing description, taken in connection with the accompanying drawings, it will be manifest that I have disclosed an extremely simple and thoroughly satisfactory form of construction which embodies the features and advantages enumerated in the statement of invention and in the foregoing description; and while I have, in the present instance, shown and described a preferred embodiment thereof as reduced to practice, it is to be understood that the construction is susceptible of modification in various particulars without departing from the spirit or scope of my invention or sacrificing any of its advantages.

I claim:

1. In a device of the character described, embodying a body and a lid closure provided each with a flange and hinge connected for opening and closing movement, the flange of the body provided with a horizontal slot slideway and a recess communicating with said slideway, a finger piece with a part slidable in said slideway, and a hook member on the lid closure flange adapted to pass through said recess into said slideway where, on movement of the finger piece in one direction to be engaged by said part for securing the lid closure in closed position, and, on movement of the finger piece in the opposite direction, to be disengaged by said part for releasing the lid closure for opening movement, said finger piece being of dimension along the outer face of the body flange to cover said slideway irrespective of the position of the finger piece, said slideway and recess being hidden from view.

2. In a device of the character described, embodying a body and a lid closure provided each with a flange and a hinge connected for opening and closing movement, the flange of the body provided with a horizontal slot slideway therethrough and a recess in its inner face communicating at an angle with said slideway, a hook member on the lid closure

flange adapted to pass through said recess into said slideway where, on movement of the finger piece in one direction, to be engaged by said part for securing the lid closure in closed position, and, on movement of the finger piece in the opposite direction, to be disengaged by said part for releasing the lid closure for opening movement, said finger piece being of a dimension to conceal said slideway along the outside face of the body flange, and means disposed in the body concealing said slideway and recess at the inside face of said body flange, whereby said slideway and recess are completely hidden at all times.

5 3. In a device of the character described, embodying a body and a lid closure provided each with a flange and hinge connected for opening and closing movement, the flange of the body provided with a horizontal slot slideway and a recess communicating at an angle with said slideway, a finger piece with a part slidable in said slideway and formed with a shoulder extension, and a hook member on the lid closure flange adapted to pass through said recess into said slideway where to be engaged by said shoulder extension for securing the lid closure in closed position, a friction member, and a second shoulder extension for maintaining the friction member in effective position.

10 4. In a device of the character described, embodying a body and a lid closure provided each with a flange and hinge connected for opening and closing movement, the flange of the body provided with a horizontal slot slideway and a recess communicating at an angle with said slideway, a finger piece with a part slidable in said slideway to come below said recess and formed with a shoulder extension, and a hook member on the lid closure flange adapted to pass through said recess into said slideway where to be engaged and disengaged by said shoulder extension accordingly as said part is moved into and out of position below said recess, and wing means on said part frictionally engaging with the body flange for maintaining the finger piece in the position to which it is moved.

15 5. In a device of the character described, embodying a body and a lid closure provided each with a flange and hinge connected for opening and closing movement, the flange of the body provided with a horizontal slot slideway and a vertical recess communicating with said slideway, a finger piece with a part slidable in said slideway to come below said recess and formed with a pair of shoulder extensions, a hook member on the lid closure flange adapted to pass through said recess into said slideway where to be engaged and disengaged by one of the said shoulder extensions accordingly as said part is moved into and out of position below said recess, and means associated with the other shoulder

extension engaging with the body flange for frictionally maintaining the finger piece in the position to which it is moved.

In testimony that I claim the foregoing as my invention, I have signed my name hereto. 70

CHARLES BERGER.
